S. Hewit,

Chunx.

No. 83853.

Patented Nov. 10. 1868.

Fig. 3.

SILAS HEWIT, OF SENECA FALLS, NEW YORK.

Letters Patent No. 83,853, dated November 10, 1868; antedated October 31, 1868.

IMPROVEMENT IN CHURNS.

The Schedule referred to in these Letters Patent and making part of the same.

To all whom it may concern:

Be it known that I, SILAS HEWIT, of Seneca Falls, in the county of Seneca, and State of New York, have invented new and useful Improvements in Churns; and I do hereby declare that the following is a full and complete description of the construction and operation of the same, reference being had to the accompanying drawings, making part of this specification, in which—

Figure 1 is a vertical section,

Figure 2 is a transverse section, and

Figure 3 is a perspective view of the dasher.

Like letters refer to like parts.

The body of the churn is constructed in the usual form, of any suitable material.

B B show the upright parts of the frame; E is the cross-head, to hold the upper end of the dasher-shaft A; H is the pinion; I is the driving-wheel, and J its shaft.

The frame is made of wood; the cross-head E is framed into the standard B B, and the frame is secured to the churn-body by means of loops or sockets, F, which are fastened to the churn-body.

On the inside of the churn, and on its opposite sides, I place four pieces, a a a a, which I call breakers, made in the form of the letter v, as shown, and which are firmly secured to the churn, and reaching about half way up its sides from the bottom. In the centre of the bottom of the churn is a pin, a', upon which the dasher stands and rotates.

Fig. 3 is a perspective view of the dasher. The lower end of the shaft A is made in the form of a frustum of a pyramid, on two opposite sides of which are attached two wings, A' A', which stand obliquely toward the shaft.

In rotating the dasher in the direction of the arrow in fig. 2, by means of the gear-wheels H and I, the cream is thrown against the breakers, and the butter thus separated.

When rotated in the opposite direction, the butter is gathered or collected into balls or masses.

In order to remove the dasher from the churn, the pins that hold the horizontal shaft in place are taken out, and the shaft displaced. The dasher-shaft, with the dasher, is then removed, and, if desired, the frame B B E can be displaced also.

What I claim as my invention, and desire to secure by Letters Patent, is—

1. The dasher A A', when constructed substantially in the manner and for the purpose set forth.
2. The dasher, when constructed as described, in combination with the breakers a a a a, as specified.
3. The combination of the body, the frame B, the dasher A A', and the breakers a a a a, as and for the purposes set forth.

SILAS HEWIT.
